ASSEMBLING MACHINE

George V. Condon, Boston, Mass., and Albin C. Eek, Webster Groves, Mo., assignors to United Shoe Machinery Corporation, Borough of Flemington, N. J., a corporation of New Jersey

Application March 11, 1940, Serial No. 323,264

6 Claims.

(Cl. 12—4)

This invention relates to machines for operating on shoes and is herein illustrated in its application to machines for assembling shoe upper parts on their lasts preparatory to the pulling-over and lasting operations. An embodiment of the invention is herein shown as applied to a machine of the type disclosed, for example, in United States Letters Patent No. 1,076,620, granted October 21, 1913, on an application of 5 Orrell Ashton, and No. 1,671,430, granted May 10, 1928, on an application of Norwood H. Knowlton.

Machines of the above type are provided with 15 grippers which engage the back-seam portion of the lasting margin of the upper and move heightwise of the upper in the operation of the machine to stretch the back-seam portion, thereby to eliminate any wrinkles or puckers therein and to straighten the backseam. Machines of 20 this type are also provided with a back rest which engages the back-seam portion of the upper adjacent to the lasting margin and determines the longitudinal position of the last and 25 upper relatively to the operating instrumentalities of the machine.

It is an object of the present invention to provide a machine of the above type in which the back rest above referred to is constructed and arranged to move heightwise of the upper simultaneously with the grippers in order that the back rest will not obstruct the action of the grippers on the upper. With the above object in view, 30 the present invention consists in the provision in a machine of the type above described of means 35 for moving the grippers heightwise of the upper to stretch the back-seam portion and for moving said back rest in the same direction simultaneously with the grippers. As herein illustrated, 40 the grippers are mounted on a carrier which is provided with a member constructed and arranged to engage a lifter on said back rest. During the operation of the grippers, the back-seam portion of the upper may be held against bodily 45 upward movement in any known manner, for example, by means of a fastening driven through the back-seam portion of the upper and into the rear end of the last, in accordance with the usual practice, but preferably, and in accordance with the present invention, the upper is gripped 50 against the last during the operation of the grippers by a lower back rest constructed and arranged to engage the back-seam portion of the upper adjacent to the top seam and to grip it firmly against the last.

55 These and other features of the invention will

now be described with reference to the accompanying drawing and pointed out in the appended claims.

In the drawing,

Fig. 1 is a side elevation of a portion of the 5 head of a machine of the type above described;

Fig. 2 is a plan view illustrating the back rest and associated parts; and

Fig. 3 is a detailed view in front elevation, partly in section, illustrating the grippers, the 10 work-engaging portion of the upper back rest, and associated parts.

In Fig. 1 there is illustrated a portion of the head of a machine for assembling shoe parts upon the lasts which is similar in its general organization and in most of its details to the machine illustrated and described in the patent to Knowlton above referred to. The machine is provided with a slide 10 which is mounted for rectilinear movement generally lengthwise of a 20 shoe in the machine and is actuated by a cam 12. The slide 10 has fulcrumed thereto at 14 a carrier 16 arranged to swing heightwise of the shoe. On the carrier there are mounted certain operating instrumentalities including gripper members 18 and 20 which engage the back-seam portion of the lasting margin and move upwardly with the carrier to apply heightwise tension to the back-seam portion of the upper. For positioning the shoe lengthwise thereof, relatively to 30 the operating instrumentalities of the machine, a lower back rest 22 and an upper back rest 24 are arranged to engage the upper in the region of the back seam. The back rest assembly is similar in its general organization to the back 35 rest assembly illustrated and described in the patent to Ashton above referred to. The back rest assembly includes a lower slide 26 and an upper slide 28 mounted in a carrier member 30 which is adjustable heightwise of the shoe. The 40 back rest assembly includes also a vertical rocker lever 32 fulcrumed at 34 on the member 30 and arranged to engage the rear portions of the slides 26 and 28, thereby to equalize the action of the 45 back rests.

In the operation of the illustrated machine, the lower back rest 22 grips the back-seam portion of the upper against the last while the grippers move upwardly to impart heightwise tension to the back-seam portion of the upper in 50 the manner common to machines of this type. The upward movement of the grippers is effected by the operation of a lever 36 by the cam 12, said lever being fulcrumed at 38 and carrying at its forward end a swivel block 40 which acts against 55

the carrier 16, all as illustrated and described in the Knowlton patent above referred to.

In order that the upper back rest 24 may move upwardly with the grippers so that it will not obstruct the stretching action of the grippers on the upper, said back rest is secured to the forward end of an arm 42 fulcrumed at 44 on the slide 28 for swinging movement heightwise of the upper, and a roll 46 on the carrier 16 is arranged to engage a lifter or finger 48 attached to the arm 42. The finger 48 has a vertical shank portion having a tongue-and-groove connection with an L-shaped bracket 50 which has a tongue-and-groove connection to the arm 42 and is adjustably secured to the arm by a clamping screw 52. The finger 48 is adjustable vertically on the bracket 50 and secured to the vertical portion of the bracket by a clamping screw 56. It will be understood that the finger 48 must be adjusted vertically following a vertical adjustment of the carrier member 30 and that a slight horizontal adjustment will be required to compensate for the varying positions of the arm 42 caused by variations in the profile of back-seam portions of shoes.

While the invention is herein illustrated in its application to a machine of the type above described, in which the back-seam portion of the upper is held against vertical misplacement on the last during the operation of the grippers solely by the gripping action of the lower back rest 22, it will be understood that the invention is equally applicable to a machine such as that illustrated in the patent to Knowlton, No. 1,671,430, above referred to, in which the back-seam portion of the upper is held against misplacement during the operation of the grippers by a tack driven through the back-seam portion of the upper and into the last at a point near the top seam of the upper prior to the action of the grippers.

Having thus described our invention, what we claim as new and desire to secure by Letters Patent of the United States is:

1. In a machine for assembling shoe parts upon their lasts preparatory to lasting, the combination with a back rest and grippers constructed and arranged to engage the back-seam portion of the lasting margin of an upper, of means for moving the grippers heightwise of the upper to stretch the back-seam portion and for moving the back rest in the same direction simultaneously with the grippers.

2. In a machine for assembling shoe parts upon their lasts preparatory to lasting, the combination with a back rest and grippers constructed and arranged to engage the back-seam portion

of the lasting margin of an upper, of a carrier for the grippers, means for moving the carrier heightwise of the upper, and means whereby the heightwise movement of the carrier is imparted to the back rest.

3. In a machine for assembling shoe parts upon their lasts preparatory to lasting, the combination with a back rest and grippers constructed and arranged to engage the lasting margin of an upper, of a carrier for the grippers, means for moving the carrier heightwise of the upper, a lifter on the back rest, and a member on the carrier arranged to engage the lifter during said heightwise movement of the carrier.

4. In a machine for assembling shoe parts upon their lasts preparatory to lasting, the combination with a back rest and grippers constructed and arranged to engage the back-seam portion of the lasting margin of an upper, of a carrier for the grippers, means for moving the carrier heightwise of the upper, a lifter on the back rest, and a roll mounted on the carrier and arranged to engage the lifter during said heightwise movement of the carrier.

5. In a machine for assembling shoe parts upon their lasts preparatory to lasting, the combination with grippers constructed and arranged to engage the back-seam portion of the lasting margin of an upper, of a lower back rest constructed and arranged to grip the back-seam portion of the upper against a last and hold it against movement relatively to the last while the grippers operate to apply heightwise tension to the upper, an upper back rest constructed and arranged for movement heightwise of the upper, and means for moving the grippers heightwise of the upper and moving the upper back rest in the same direction simultaneously with the grippers.

6. In a machine for assembling shoe parts upon their lasts preparatory to lasting, the combination with grippers constructed and arranged to engage the back-seam portion of the lasting margin of an upper, of a lower back rest constructed and arranged to grip the back-seam portion of the upper against a last and hold it against movement relatively to the last while the grippers operate to apply heightwise tension to the upper, an upper back rest constructed and arranged for movement heightwise of the upper, a carrier for the grippers, means for moving the carrier heightwise of the upper, a lifter on the upper back rest, and a member on the carrier arranged to engage the lifter during said heightwise movement of the carrier.
